BOTTLE OR SIMILAR ARTICLE

Phillip A. Sollomi, Kansas City, Mo.

Application August 23, 1955, Serial No. 37,634

Term of patent 14 years

(Cl. D58—6)

Fig. 1.

Fig. 2.

Fig. 3.

Fig. 4.

Fig. 5.

Fig. 6.

Fig. 1 is a elevational view of a bottle, showing my new design.

Fig. 2 is a top plan view thereof.

Fig. 3 is a fragmentary cross sectional view thereof taken on the line 3—3 of Fig. 1.

Fig. 4 is a side elevational view thereof taken from one corner.

Fig. 5 is a fragmentary cross sectional view thereof taken on the line 5—5 of Fig. 1.

Fig. 6 is a bottom plan view thereof.

The side not shown is the same as the side shown.

I claim:

The ornamental design for a bottle or similar article, as shown and described.
